METHOD OF AND MACHINE FOR
PRODUCING HAIRPINSAlfred Carlyle Day, Redfern, near Sydney, New
South Wales, AustraliaApplication September 24, 1940, Serial No. 358,185
In Australia September 28, 1939

8 Claims. (Cl. 140—87)

This invention relates to the production of hair-pins and particularly those known as bobby-pins which hitherto have been produced from previously produced "half round" or flattened wire, that is wire with a flat opposite a convexity, or which has been flattened, in cross section.

And this invention has been specially devised to provide an improved method of, and machine for, producing hair-pins whereby the previous separate operation of forming the wire "half round" or "flat" is avoided, and the production of the pins is simplified, expedited and cheapened, and ordinary wire round in cross section is drawn from a coil, straightened by being drawn through straightening means of any convenient known construction, then drawn between a pair of forming rollers, of which the peripheries are so shaped in cross section that the indrawn round wire is formed to desired cross sectional shape such as "half round" with the flat upwards, or flat, and then passes through feed accommodating means, and thence into parting and forming dies in a suitable press whereby a length of the wire or blank to form two pins is severed and (1) advanced transversely forward from the path of the incoming wire, and the twin blank is then advanced successively to transverse or laterally forward positions where it is (2) arched, has each end slightly angled, is transversely corrugated as desired, and has a length inwardly from each end bent upwards in a direction towards the arch, by operation of one die, (3) the partially formed pair of pins at the next advanced position upon another lower die has each diagonally up-standing end bent inwardly and downwardly towards the middle or arch of the twin blank by another part of the first die, (4) at a still further advanced position, on another co-acting lower die has each end bent down upon the arch, (5) whereafter at another advanced position the bow end of each pin is bent downwardly and engaged by a spring latch, and a cutting punch severs the joined pair of fully formed pins so as to leave a rounded end on each at the severance, and as the severing is completed the two pins fall from the machine.

And in order that the invention and a practical application thereof will be readily understood the same will now be described with reference to the accompanying drawings, in which:

Figure 1 is a perspective of the improved machine, known wire straightening means and a coil of wire upon a turntable not being shown.

Figure 2 is a sectional elevation on the plane 2—2 in Figure 1;

Figure 3 is a fragmentary partial sectional perspective upon the plane 3—3 in Figure 1.

Figure 4 is a diametrical view of one set of forming rollers.

Figure 5 is an enlarged transverse section of the transverse advancing means.

Figure 6 is a fragmentary partial sectional elevation of the aligning fingers acting in association with the transverse advancing means.

Figure 7 is a longitudinal section on the line 7 in Figure 2 and partly in elevation of the wire severing means.

Figure 8 is a fragmentary sectional elevation in the direction of the arrows on line 8—8 in Figure 7.

Figure 9 is a fragmentary perspective of the guiding and holding means for the wire entering the dies.

Figure 10 is a longitudinal section on the line 10 in Figure 2 and partly in elevation, of the arching and end bending dies.

Figure 11 is an end elevation on the line 11—11 in Figure 10.

Figure 12 is a longitudinal elevation on the line 12 in Figure 2 and partly in section, of the end inbending dies.

Figure 13 is a sectional elevation on the line 13—13 in Figure 12.

Figure 14 is an end elevation on the line 14—14 in Figure 12.

Figure 15 is a longitudinal section on the line 15 in Figure 2 and partly in elevation.

Figure 16 is a fragmentary plan on the line 16—16 in Figure 15.

Figure 17 is a longitudinal section on the line 17 in Figure 2 and partly in elevation.

Figure 18 is a sectional plan on the line 18—18 in Figure 17.

Figure 19 is a fragmentary perspective of the pin ejection guiding means, and

Figure 20 is a perspective of a produced hairpin.

A round wire from a coil, upon a convenient turntable not shown, is gripped, drawn forward and formed into desired cross sectional shape such as, having a flat opposite a convexity, or flat, by a pair of conveniently mounted and driven forming rollers such as 20 and 21 the former having a plain periphery and the latter an annular channel 22, and the so formed wire 23, Figure 7, emerging from the rollers 20 and 21 passes straight or diametrically through a sinuous track 24 formed by concave recesses in an upper plate 25 and a lower plate 26 and a cover plate 27, such path being specially provided and so formed to

accommodate the advancing wire between the discharge of the rollers 20 and 21 and the entrance to parting off and forming dies where the entered wire is gripped and held while a section is severed. The complementary parts of forming dies and cutters are mounted upon a plate 28 secured to the base 29, and the reciprocating plate 30 of a convenient die press arranged to be conveniently operated.

Referring to Figures 7, 8 and 9, in a block 31 on the plate 28 is resiliently supported by a spring 32 a wire guide 33 with upstanding jaws 34 and wire slots 35 through which the wire enters the machine, and at opposite end the plate 30 carries a downwardly tapered aligning peg 36 above an accommodating socket 37 in said block 31, said peg 36 to engage and move over or keep in alignment the inner and free or leading end of the wire 23.

Above the guide 33 on the plate 30 is a clamping member 38 to grip and hold the wire 23 while semicircular shaped cutters 39 at each end of the dies on plate 30 above co-acting sockets 40 sever the wire and trim the opposite end to leave a rounded end 41, Figures 7 and 20.

During the holding of the wire by the guide 33 and clamping member 38 the wire which is being fed forward by the rollers 21 and 22 sinuates into and is accommodated in the sinuous path 24, and immediately the wire is released upon the rising of plate 30 the sinuated length straightens out and the end shoots forward into the machine.

The severed length of wire, Figure 7, for a pair of pins is then under the keeper plate 42 consisting of two sections one each secured to opposite side of a jaw housing block 43, Figure 2, secured to the plate 28 and within which is a recess 44 wherein are a pair of vertically resilient jaws 45 and 46, the former being mounted upon rods 47 with springs 48 thereabout and having a longitudinally or forwardly spaced plurality of transverse recesses 49a, 49b, 49c, 49d, and 49e, to accommodate the wire of a twin blank, and later, a partially formed pair of pins, and a punch passage 50. The lower jaw 46 which has upstanding sides 51, Figure 7, which are spaced sufficiently to slidably embrace the upper jaw and project forwardly, Figure 2, and slide in the slots 52, have like recesses 52a, 52b, 52c, 52d and end 52e, is mounted upon studs 53, Figure 2, and supported upon springs 54 about said studs, all accommodated in a recess 55 in a reciprocating bar 56 which is reciprocably accommodated in said block 43, and has an upwardly bevelled or ramped rear end 57 where it is connected by a laterally projecting stud 58 at each side to a tension spring 59 which is anchored to a post 60 of a bracket 61 rearwardly extended from the plate 28, a bracket 62 secured to the reciprocating plate 30 and having a cam projection 63 moving said bar 56 and jaw 46 forwardly at each upward movement of said plate 30.

The engagement of tensioned jaws 45 and 46 in addition to the advancement of the partially formed pins being effected hold them so that they will not fall sidewardly.

After the twin blank enters the machine and is in the position shown in Figure 7, the next upward stroke of plate 30 raises the clamping member 38 thus releasing the incoming wire 23, and the sinuated up length thereof in the sinuous track 24 instantly straightens out by shooting forward into the machine and is then under the plate 42 and in the slots 49a and 52a of the jaws

45 and 46, and said upward stroke of plate 30 operates the advance means which move the severed wire transversely or laterally forward into recess 49b and 52b, Figures 2, 5 and 10, where it lies between upper and lower dies 64 and 65, the latter having wire stops 66, and between said dies upon the next downstroke of the press the wire will be centrally arched and have transverse kinks or corrugations 67 formed towards each end whereat a slight bend 68 is effected, and upon release the ends will spring back, all as in Figure 10.

At next upstroke of the press the partially formed blank will be moved into the next recess 49c and 52c and onto die 69 against stops 69x, Figure 12, so that during the next downstroke of the plate 30 the forwardly disposed pins 70 on die 69 will press the ends down into the die against the shoulders 71 thereof and cause each end of the blank to be drawn into the position shown.

The next upstroke of the plate 30 will move the blank forward into another recess 49d and 52d and onto die 72 and against stops 73, Figure 15, where during the next downstroke of the plate 30 the punches 74 press its ends down as shown.

As the aligning fingers 75, Figures 1 and 6, depending from the plate 30 descend, they engage the wires thereunder, and any that may not be in exactly correct register with the dies upon which they should be, are moved into that position.

The nearly completed joined pair of pins at next upstroke of the plate 30 are moved forward into next recess 49e by the end 52e, of the jaw 46, Figures 17 and 18, where at next downstroke of said plate the bow end of each pin will be bent down by a punch 76 against the guide 77 past, and be held down by, a spring latch 78, and the double edged punch 79 with concave opposite edges 80 will sever the pair of pins to leave rounded ends 84, Figure 20, the cutting falling away through passage 81 in the block 43, and as the punches 76 and 79 retire each completed pin 82, Figure 20, falls and is directed into passage 83, Figure 2, wherethrough they fall from the machine and are received and collected thereunder or directed by convenient chute elsewhere desired.

I claim:

1. In the production of hair pins, the step of moving a length of wire sufficient to form two hair pins severed from that fed from a coil, transversely forward from the path of the incoming wire and successively so advancing it to successive positions at each of which it is successively operated upon to complete production of two separate hair pins.
2. Improved machine for producing hair pins, comprising rollers to form and/or advance a wire from a coil, a sinuous path from said rollers to a die press to accommodate wire advanced from the rollers while its end is temporarily held, and a die press in which are means for (1) holding an entered length of the wire, (2) severing that length and shaping the ends as desired, (3) retaining the severed length, (4) moving it transversely forward out of the path of incoming wire, (5) successively moving the partially formed blank, and (6) co-acting dies on a plate upon the base and on an upper reciprocating plate of the press, to (a) arch the blank at mid-length, and transversely kink or corrugate it towards each end, bend each end

in towards the arch and at each end slightly angle it, (b) to further bend each end towards the arch, (c) to bend each end down upon the arch, and (d) to sever a so formed joined pair of hair pins.

3. Improved machine for producing hair pins, comprising rollers to form and/or or advance a wire from a coil, means to accommodate and control wire advanced from the rollers while its end is temporarily held, and a die press in which are; a wire guide and clamp at the entering end, a die at the inner or leading end to trim the wire end, a die just inwardly of the guide to sever the wire and trim the trailing end, a path to receive and hold the entered and severed length of wire, upper and lower ratchet like jaws working one within the other tensionally and having ratchet like recesses to accommodate transversely positioned wire, and disposed transversely across said jaws, successive lower dies on a plate on the press base, and co-acting dies upon the reciprocating plate of the press, to (a) arch the blank at mid-length, transversely kink or corrugate it towards each end, bend each end in towards the arch and at each end slightly angle it, (b) to further bend each end towards the arch, (c) to bend each end down upon the arch, and (d) to sever a so formed joined pair of pins.

4. In and for machines for production of hair pins of the type having means for accommodating the wire moving forward from forming or feed rollers to a die press while the entered end is temporarily held in said press, a vertically superimposed pair of plates each having a longitudinally spaced plurality of concavities in the edges and positioned in longitudinal relation so that the ends of the concavities in one slightly overlap those in the other and a cover plate across the path providing a straight and also a sinuous path for a fed wire to pass therethrough and to buckle thereinto when its leading end is temporarily held, and from which it may straighten thereout into a machine immediately said end is released.

5. Improved method of producing two hair pins simultaneously from round wire, consisting in reforming the wire by rolling it into a cross sectional shape having a transverse flat and an oppositely disposed convexity, or flat, the reformed wire feeding forward continuously from said rollers, passing the reformed wire through feed accommodating means to a press, therein severing a desired length for two pins, moving said length transversely forward from the path of incoming wire, and during successive strokes of the press successively advancing the length transversely forward and (1) arching it at mid-length, corrugating it transversely towards each end and slightly angling each end, (2) bending the upstanding ends inwardly and towards the arched portion, (3) bending said ends down upon the arched portion, and (4) severing the so formed joined pair of pins.

6. Improved method of producing two hair pins simultaneously from round wire, consisting in, reforming the wire by rolling it into a cross sectional shape having a transverse flat and an oppositely disposed convexity, or flat, the reformed wire feeding forward continuously from said rollers, passing the reformed wire through feed accommodating means to a press, therein holding the entered wire, severing a desired length for two pins while the wire fed forward from the feed rollers sinuates into said accommodating means and shoots into the press when the entering end is released, moving the severed length for two pins transversely forward from the path of incoming wire, and during successive strokes of the press successively advancing the length transversely forward and during said strokes (1) arching it at mid-length, corrugating it transversely towards each end, slightly angling each end, (2) bending the upstanding ends towards the arched portion, (3) bending said ends down upon the arched portion, and (4) severing the so formed joined pair of pins.

7. Improved method of producing two hair pins simultaneously consisting in, passing wire of requisite cross section through continuously feeding rollers and thence through feed accommodating means to a press, therein severing a desired length for two pins, moving said length transversely forward from the path of incoming wire by pressure and ratchet functioning means disposed medially of the press, and during successive strokes of the press successively advancing said length transversely forward, and during said strokes (1) arching it at mid-length, corrugating it towards each end and slightly angling each end, (2) bending the upstanding ends inwardly and towards the arched portion, (3) bending said ends down upon the arched portion and (4) severing the so formed pair of pins.

8. Improved method of producing two hair pins simultaneously consisting in, passing wire of requisite cross section through continuously feeding rollers, sinuating the forwardly fed wire between feeding rollers and a press in which the wire is acted upon, intermittently freeing the wire entered in the press and allowing the sinuated part to shoot into the press, holding the so entered wire, severing a length for two pins, moving the severed length transversely forward from the path of incoming wire, successively moving the length transversely forward, (1) arching the length at mid-length, transversely corrugating it towards each end and slightly angling each end, (2) bending the upstanding ends inwardly and towards the arched portion, (3) bending said ends down upon the arched portion, and (4) severing the so formed joined pair of pins.

ALFRED CARLYLE DAY.
